UNITED STATES PATENT OFFICE.

MARTIN ZAWISTOWSKI AND NICOLAS KOMOW, OF BROOKLYN, NEW YORK, ASSIGNEES
TO UNITED STATES CLOTH CUTTING MACHINE CO., INC., OF NEW YORK, N. Y., A
CORPORATION OF NEW YORK.

STRAIGHT-KNIFE CLOTH-CUTTING MACHINE.

1,277,812.

Specification of Letters Patent.

Patented Sept. 3, 1918.

Application filed July 28, 1917. Serial No. 183,211.

To all whom it may concern:

Be it known that we, MARTIN ZAWISTOWSKI and NICOLAS KOMOW, both citizens of the United States, and both residing in the 5 borough of Brooklyn, in the county of Kings, city and State of New York, have invented a new and useful Straight-Knife Cloth-Cutting Machine, of which the following is a specification.

10 The invention is an improved cloth-cutting machine of the reciprocatory straight-knife type, the objects being to simplify and lower the cost of construction and reduce dimensions, to overcome vibration and looseness, to facilitate manufacture, assemblage, repair, and interchange of parts, to provide an improved presser-foot construction, which may yield upward automatically in addition to being vertically adjustable, and generally to improve the mechanical organization of the machine. The preferred embodiment of the machine will now be briefly described and its novel features and combinations more particularly pointed out in the 25 appended claims.

In the drawings:

Figure 1 is a view, partly in side elevation and partly in vertical section, of the complete machine, intermediate portions of 30 which are broken away for economy of space;

Fig. 2 is a detail vertical sectional view on the line 2—2 of Fig. 1;

Fig. 3 is a front elevation, with the front 35 cover removed;

Figs. 4 and 5 are detail views in plan and front elevation, respectively, of the slide-block;

Fig. 6 is an inner face view of the crank 40 disk;

Fig. 7 is a front elevation of the motor and front cover, with the parts carried thereby, a portion of the latter being broken away;

45 Fig. 8 is a top plan of the motor bracket;

Fig. 9 is a front elevation thereof;

Fig. 10 is a top plan of the forward portion of the motor bracket with a top plate applied thereto;

50 Fig. 11 is a bottom plan corresponding to Fig. 10;

Fig. 12 is a horizontal section on an en-

larged scale through the upper portion of one of the guide rods;

Fig. 13 is a plan view of the machine as 55 a whole;

Fig. 14 is a front elevation of a portion of the front cover, showing a guide box with its cover section removed;

Fig. 15 is a view looking upward at the 60 lower end of the parts represented in Fig. 14;

Fig. 16 is an end view of said cover section;

Fig. 17 is an inside face view thereof; and 65

Fig. 18 is a fragmentary view, showing the complete guide box partly in vertical section and partly in elevation.

2 is a base, such as these machines customarily possess, and from which rises a 70 support, whereon the knife and driving mechanism are mounted and the former guided. The support in the present instance comprises a fixed standard section 3, in the front of which the major portion of the 75 knife 4 is guided, and a motor bracket 5, which is separate from the standard on the one hand and the motor 6 on the other hand and is capable of being removed and interchanged with brackets of other heights and 80 of being shifted upon the standard to adjust the alinement of the guides. Upon this bracket and forming a part of the intermediate unit of the machine is a triple slide-block guide, 7, 7, 7A.

85 The top of the standard has a horizontal limb 8, upon which the bracket 5 is planted in rearwardly projecting relation to the standard. At the top of the bracket is a seat 9, to which the motor field-frame is secured by screws 9^a, and at the front is a face portion 10, set back from the front lines of the standard and extended upward above said seat. The base of the bracket is united toward the rear with the limb 8 by a vertical screw 11, permitting a slight degree of swiveling of the bracket relatively to the standard under the control of a pair of horizontal set screws 12, threaded through a bifurcated, rear lower portion of the bracket 100 to bear upon opposite sides of a reduced extremity 13 of the bracket. The face portion of the bracket is formed with lower and upper forward projections 14 and 15, dis-

posed approximately over the transverse lines of the standard. The lower projection 14 is slotted or doubled, as shown in Figs. 9 and 11, and depressed below the base of 5 the bracket so as to straddle the top of the standard, with room for a limited amount of lateral movement about the screw 11.

The guides 7 and 7^A are mounted in the face portion of the bracket and in its upper 10 and lower projections, the guides being three in number and disposed in the form of a triangle, two in front and the other centrally in rear thereof. To accommodate the rear guide 7^A the face portion 10 is constructed 15 with a longitudinal recess or opening 16, see Fig. 9. This rod is received at its opposite ends in aligned openings 17 and 18 in the top of the bracket portion 10 and in the forward portion 19 of its base, and is held against 20 longitudinal displacement therein by abutment against the top of the standard and against a plate 20 applied to the top of said face portion. The forward pair of rods 7 are similarly held in openings 21 and 22 in 25 the projections 14 and 15, and are retained by the said plate 20 and by bottom plates 23 secured to the under sides of the lower projections.

The slide-block 24, shown in detail in Figs. 30 4 and 5, is constructed with upper and lower pairs of lateral bearings 25, to embrace the forward guides 7, and with rearwardly projecting bearings 25^A entering the recess 16 to engage the rear guide 7^A. Projecting forwardly from the slide-block are 35 means for connection with the knife 4 and the pitman 26 by which it is driven from the motor, the said means comprising a vertical lug 27 on the lower part of the slide-block, 40 to which the upper end of the knife is directly secured by a bolt, and a wrist-pin 29 screwed into the upper portion of the slide-block and pivotally receiving the lower end of the pitman.

45 The motor 6 is of the construction disclosed in our copending application filed March 15, 1917, Serial No. 154,913, for rotary knife machine, to which reference may be had for a detailed description, and where- 50 in claims generic to the two cases, based upon this feature, will be found. In the present instance the motor is set horizontally, instead of vertically, with its armature shaft 30 ranging fore and aft. Upon the 55 forward end of this shaft, outside the field-frame, is a counterweighted eccentric disk 31, which is located above the slide-block and its guides. The upper end of the pitman 26 is mounted by means of a ball bearing 32 60 upon a crank pin 33 fixed in the crank, and extends downward in front of the crank and the slide-block to connect with the wrist-pin 29 as described.

65 Lubrication of the front bearing 61 of the motor shaft and of the slide bearing of

the slide-block is advantageously effected through the provision of an oil duct 34, extending downward from an oil cup 62 through the motor frame to the shaft and thence to a cupped opening 35 in the plate 70 20, by which the oil is admitted to the upper ends of longitudinal cavities 36 in the guide rods 7 and 7^A. Openings 37, leading outward from these cavities through the walls of the tubes and communicating with exterior grooves 38, conduct the oil thus received to the outside of the guide rods, where it is further distributed by the action of the slide-block as it moves up and down. Lubrication of the pitman bearing 32 is also effected from the same source by means comprising a stationary tube or short duct 63 inserted in the front of the motor frame in position to divert a portion of the oil flowing through the channel 34, an annular 80 trough 64 in the rear face of the crank, into which this tube delivers, and a short radial channel 65 drilled in the crank and crank pin, to conduct the oil urged by centrifugal force from said trough to a longitudinal passage 66 in the interior of the pin, from which the oil reaches the bearing 32 through a lateral hole 67.

The rearwardly projecting handle 39, by which the machine is advanced in the direction of the cut, is screwed at 40 to the bottom of the rearwardly overhanging portion of the field-frame of the motor. This handle carries the customary switch 41, by which the motor is stopped and started, such switch 95 and its connections, which lead through the handle, being well understood and requiring no special illustration. The connection piece 42 for the reception of the usual connection member on the end of an electrical cable is 100 also attached to the field-frame, preferably at its top, the terminals of the said piece 42 being connected with the motor windings, as will be understood. It will thus be seen that the electrical parts of the machine are 105 all embodied in a unit by themselves, which may be removed and replaced substantially independently of the purely mechanical parts.

The operating parts at the front of the 110 machine are inclosed and protected by a cover 43, comprising a substantially circular portion applied to the front boss 44 of the motor frame and inclosing the crank and the upper part of the pitman, and a downward extension 45 inclosing the slide-block guides, the lower part of the pitman, and the upper portion of the knife. The remainder of the knife is guarded by a vertical bar 46, which is slidably and adjustably mounted upon the front of the cover 43, and the lower end of which carries a presser-foot 47. This bar passes through a guide box 48 upon said cover, to which it is normally connected by a pivoted catch 49 115 120 125 130

mounted in a block 50 on the bar, the top of the catch engaging beneath a lug 51 on the front or cover section 52 of the said guide box. The catch 49 and lug 51 constitute a detachable coupling, which normally holds the presser-foot at the desired position, but permits the bar and presser-foot to be raised freely when desired. The catch 49 holds the bar and presser-foot to the part 52 with respect to upward pressure upon the presser-foot; or upon releasing the catch the presser-foot and bar may be lifted freely. The abutment of the block 50 against the top of the guide box 48 holds the parts against slipping downward. The position of the block lengthwise upon the bar 46 may be shifted by virtue of the provision of a clutch 53, thus adjusting the height at which the presser-foot is normally maintained. This clutch, the manner in which the block 50 coöperates with the bar and the guide box, and the catch 49 are all known features of construction which do not require more detailed illustration or explanation.

The improvement in this part of the machine consists, specifically speaking, in making the cover section 52 of the guide box vertically yieldable against the action of springs, so that the presser-foot may rise automatically under excessive pressure, as when riding over a high spot. In other words the relatively stationary part to which the bar and presser foot are normally coupled by catch 49 and lug 51 is capable of limited self-restoring movement. The preferred construction is illustrated in Figs. 13 to 17, wherein it will be seen that the body of the guide box has a central rectangular grooved way 54 for the bar 46 and vertically elongated side cavities 55 for the reception of helical compression springs 56.

The cover section 52, which carries the lug 51, has a longitudinal rib 57 upon its inner face which is also guided in the groove 54, and a pair of inwardly projecting pins 58 which engage the lower ends of the springs, which are thus compressed by upward movement of the said part and restore it to its lowermost position as soon as the external pressure is relieved. The cover section of the guide box is held in place by screws 59 passing loosely through vertical slots 60 in said section and screwed into the body.

What we claim as new is:

1. In a reciprocating straight-knife cloth-cutting machine, the combination of a base, a support rising therefrom, a knife operating in front of the support, a motor mounted on the support, a crank upon the forward end of the motor shaft, a pitman extending downward from the crank, a triple guide below the crank and behind the pitman, and a slide-block connecting with the pitman and

knife and having a triangle of bearings coöperating with the triple guide.

2. In a reciprocating straight-knife cloth-cutting machine, the combination of a base, a support rising therefrom, a knife operating in front of the support, a motor mounted on the support, a crank upon the forward end of the motor shaft, a pitman extending downward from the crank, three vertical guide rods mounted below the crank and behind the pitman, the same being disposed two in front and one centrally in rear, and a slide-block having lateral bearings slidably engaging the front pair of rods and rearwardly projecting bearings engaging the rear rod and forwardly projecting means for connection with the pitman and knife.

3. In a reciprocating straight-knife cloth-cutting machine, the combination of a base, a support rising therefrom, a knife operating in front of the support, a motor mounted on the support, a crank upon the forward end of the motor shaft, a pitman extending downward from the crank, three vertical guide rods mounted below the crank and behind the pitman, the same being disposed two in front and one centrally in rear, a slide-block having lateral bearings slidably engaging the front pair of rods and rearwardly projecting bearings engaging the rear rod, and a wrist-pin and a knife-lug projecting forward from the slide-block at different heights and constituting the connections respectively for the pitman and knife.

4. In a reciprocating straight-knife cloth-cutting machine, the combination of a base, a support rising therefrom, the upper part of the support being set back and provided with a vertical recess in its face, a knife guided in the support below said part, a motor on top of the support, a crank on the forward end of the motor shaft, a pitman extending downward from the crank, three guide rods, one in said recess and the other two in front, and a slide-block having bearings coöperating with the respective rods and connected with the pitman and knife.

5. In a reciprocating straight-knife cloth-cutting machine, a base, a standard, a knife guided in the standard, a rearwardly projecting motor bracket mounted on the standard, a motor planted on the motor bracket, a crank and a downwardly extending pitman on the forward end of the motor shaft, in combination with guides carried wholly upon the front of said motor bracket, and a slide-block on said guides connecting with the pitman and knife.

6. In a reciprocating straight-knife cloth-cutting machine, the combination with a base, standard and knife, of a rearwardly projecting motor bracket mounted on and having a vertically extended face portion

- carrying guides wholly thereon, a motor on the rearwardly projecting portion of the motor bracket behind said vertically extended face portion, a crank and a downwardly extending pitman on the forward end of the motor shaft, and a slide-block on said guides on the face portion of the motor bracket connecting with the pitman and knife. 35
- 5 7. In a reciprocating straight-knife cloth-cutting machine, the combination with a base, standard and knife, of a rearwardly projecting motor bracket mounted on the standard and having a vertically extended 40
- 10 face portion set back from the front of the standard and provided with forward projections at top and bottom, guides extending between and carried wholly by said projections, a motor planted on the motor 45
- 15 bracket behind said vertically extended face portion, a crank and pitman on the forward end of the motor shaft, and a slide-block on the guides connecting with the pitman and knife. 50
- 20 8. In a reciprocating straight-knife cloth-cutting machine, the combination with a base, a support rising therefrom, a knife, a motor on the support having a shaft and a forward shaft bearing, of means for supplying lubricant to said motor shaft bearing, a crank-disk on the forward end of the motor shaft having an annular trough in its rear face, a stationary tube connected with said lubricant supplying means and projecting into 55
- 25 said trough, a crank-pin fixed to the crank-disk, a pitman and a pitman bearing upon the crank-pin, the pitman connected with the knife, said crank-disk and crank-pin having connecting channels for leading the oil from the trough to the pitman bearing. 60
- 30 9. In a reciprocating straight-knife cloth-cutting machine, the combination of a presser-foot and vertical bar, a guide for the bar wherein the bar is movable, one portion of the guide being vertically yieldable and pressed downward by springs, and a detachable coupling between the bar and yieldable portion of the guide. 65
- 35 10. In a reciprocating straight-knife cloth-cutting machine, the combination of a presser-foot and vertical bar, a supporting member, a guide box thereon having a vertically yieldable cover and spring cavities containing springs normally holding the cover down, and a catch for connecting the bar and cover. 70
- 40 11. In a reciprocating straight-knife cloth-cutting machine, the combination with a base, uprising support, vertical knife, motor-driven means for operating the knife, and a front cover, of a presser-foot and vertical bar, means on the cover for guiding the bar, an adjustable block on the bar, a member spring-pressed downward, and means for catching the adjustable block to said member. 75
- 45 MARTIN ZAWISTOWSKI.
50 NICOLAS KOMOW.
